UNITED STATES PATENT OFFICE.

JOSEPH HUPPMANN, OF NEW YORK, N. Y.

DESIGN FOR A CIGARETTE SHOW-CARD.

SPECIFICATION forming part of Design No. 14,322, dated September 25, 1883.

Application filed May 16, 1883. Term of patent 7 years.

To all whom it may concern:

Be it known that I, JOSEPH HUPPMANN, of the city, county, and State of New York, have invented and produced a new and original 5 Design for Cigarette Show-Cards, of which the following is a full, clear, and exact description, reference being had to the accompanying photograph.

The design will first be described in connection with all that is necessary to a full understanding thereof, and then pointed out in the claim.

A is the card, inclosed within a frame, B, and having a border, C, of any desired ornamental design. D is the ornamental parallelogrammic figure, or there may be two or more of such figures, D D, arranged one below the other. Each or either of these figures D is made up of a series of horizontal body-lines, 15 b b, and opposite side column or vertical body-lines c c. These horizontal and vertical body-lines b c combined, which form spaces between them for the cigarettes E and for indicating on the card the number, brand, description, 20 size, and price of the cigarettes, may be bordered by shade-lines to improve the relief ap-

pearance of the body-lines. Said body or bar-like lines b c, as combined, present the appearance, in relief, of a bar-like structure, the bars of which are arranged to cross each other 30 at right angles, and are united with each other where thus crossing by figures e e, representing screws or fastenings.

The card itself may be headed by an armorial device, here represented as mainly consisting of griffins rampant on a scroll, G. Above the parallelogrammic figure A is space 35 for a word, as shown.

I claim—

A design for cigarette show-cards, consisting of a parallelogrammic figure, A, made up of a series of horizontal body-lines, b, and the vertical side column-like lines, c, arranged as described, and ornamented by figures e, resembling screws, and the whole presenting in appearance a series of united bars or a bar-like structure, as herein shown and described.

JOSEPH HUPPMANN.
